(57) **CLAIM**

The ornamental design for an invertible multifunction shovel, as shown and described.

DESCRIPTION

FIG. 1 is a forward perspective view of an invertible multifunction shovel in accordance with the present invention;

FIG. 2 is a side forward perspective view of an invertible multifunction shovel in accordance with the present invention;

FIG. 3 is a top perspective view of an invertible multifunction shovel in accordance with the present invention;

FIG. 4 is a lower perspective view of an invertible multifunction shovel in accordance with the present invention; and,

FIG. 5 is a rearward perspective view of an invertible multifunction shovel in accordance with the present invention.
